(57) **CLAIM**

The ornamental design for a releasable pry bar, as shown and described.

DESCRIPTION

FIG. 1 is a perspective view of a releasable pry bar; and, FIG. 2 is a side view thereof, wherein the opposing side view is a mirror image.

The claimed design is a tool for applying force on a work-piece. The broken lines in the drawings illustrate features of the releasable pry bar that form no part of the claim.
